TWO-WAY RADIO OR SIMILAR ARTICLE

Rudolph W. Kroopp, Palatine, Ill., assignor to
Motorola, Inc., Franklin Park, Ill.

Filed July 13, 1970, Ser. No. 23,916

Term of patent 14 years

Int. Cl. D14—03

U.S. Cl. D26—14

FIG. 1

FIG. 2

FIG. 3

FIG. 4

FIG. 1 is a perspective view of a two-way radio or similar article showing the front, top and one side of my new design;

FIG. 2 is a view of the housing side not shown in FIG. 1;

FIG. 3 is a view of the bottom of the two-way radio, and

FIG. 4 is a view of the rear side of the two-way radio shown in FIG. 1.

I claim:

The ornamental design for a two-way radio or similar article, substantially as shown.
